(57) **CLAIM**

The ornamental design for a glazing bead for use with a window frame extrusion, as shown and described.

DESCRIPTION

FIG. 1 is a perspective view of a glazing bead for use with a window frame extrusion;

FIG. 2 is a fragmentary left side elevational view of the glazing bead for use with a window frame extrusion;

FIG. 3 is a fragmentary front elevational view of the glazing bead for use with a window frame extrusion;

FIG. 4 is a fragmentary top plan view of the glazing bead for use with a window frame extrusion;

FIG. 5 is a fragmentary rear elevational view of the glazing bead for use with a window frame extrusion; and,

FIG. 6 is a fragmentary bottom plan view of the glazing bead for use with a window frame extrusion.
